MILD WEATHER CONTROL

Arthur V. Sampsell, La Fayette, Ind., assignor to
Sears, Roebuck & Company, Chicago, Ill., a
corporation of Delaware

Application February 7, 1936, Serial No. 62,796

6 Claims. (Cl. 236—46)

This invention relates to a mild weather control for hot air furnaces. At present the automatic stoker is generally accepted as desirable furnace equipment for private homes. The greatest problem in their use pertains to the automatic control of a small fire in a furnace during relatively mild weather when little demand for heat is placed upon the furnace. Under this condition the fire quite frequently burns out, and when the thermostat controlling the stoker motor finally demands heat, the stoker will continue to feed coal to the burnt-out fire until discovered and rendered inoperative. This invention effectively eliminates this problem from stoker use by providing a fire pilot control. It is also desirable to employ a blower or fan in conjunction with a warm air furnace which will provide a means of carrying off, by adequate conduits, the cold air from certain parts of the heated house, circulating it through a suitable filter and the warm air chamber and bonnet of the furnace, and thence driving it in warmed condition back into the rooms. This invention combines the desirable feature of fire pilot control with the use of a blower for warm air furnaces.

An object of the invention is to provide an automatic means of piloting a fire for a warm air furnace, during relatively mild weather, which employs a blower for circulating air.

Another object of the invention is to provide a means for automatically operating the stoker for predetermined time intervals whilst rendering the air circulating means inoperative.

A further object of the invention is to provide a means of operating the blower of a warm air furnace when a limit control in the stoker motor circuit has rendered the latter inoperative, while the thermostat is still calling for heat.

These and other objects are attained by the means described in the specification and illustrated in the accompanying drawings, in which:

Fig. 1 is an elevational plan view of the assembly of the devices which comprises the controlling unit of my invention; the different devices being connected by a preferred wiring system; the blower, stoker motor and limit control being shown diagrammatically.

Fig. 2 is an elevational cross sectional view taken on line 2—2 of Fig. 1.

Fig. 3 is a cross sectional view taken on line 3—3 of Fig. 2.

Fig. 4 is a diagrammatical view of the wiring system of the device.

Fig. 5 is a rear elevational view of a warm air

furnace, the rear casing being broken away to show the arrangement of parts, some of the latter being shown in cross section for clearness.

Fig. 6 is a simplified wiring diagram of the device.

Generally, my device consists of a fire pilot control which has a time controlled mechanism adapted to regulate the inclination of a pivoted mercury tube having a pair of switch contacts at its two extremities. The blower circuit is controlled by one pair of these contacts whilst the stoker is operated through the other pair of contacts. The time controlled mechanism generally allows the mercury tube to remain in the inclined position which closes the contacts to the blower but for a short predetermined time tilts the tube to close the contacts to the stoker motor. The last operation is devised to occur at regular intervals so that the stoker must necessarily feed the fire at such times, thus keeping it burning when there is no demand for heat by the room thermostat.

The room thermostat is wired in the stoker motor circuit in the usual manner. A limit control located above the furnace bonnet, is placed in the stoker motor circuit and acts to break the circuit when the heat in the bonnet becomes excessive. This thermostat stoker motor circuit is independent of the fire pilot control circuit so that in relatively mild weather the fire pilot control will operate the stoker to feed a sufficient amount of coal to the fire to keep it burning, but in cold weather the thermostat, demanding heat, will operate the stoker motor in the usual manner.

As has been said, the blower mercury switch contacts are generally "closed", and are wired in series to the stoker motor circuit which is thermostatically operated. Thus when the thermostat demands heat the stoker motor and the blower will operate in unison to furnish the required heat to the rooms. However in mild weather, the fire pilot control will operate the stoker, the blower being rendered inoperative by the necessary inclination of the mercury tube, the heat of such stoker activity thereby being allowed to remain about the furnace bonnet.

The blower mercury switch contacts are so wired in the stoker motor circuit as to permit the blower to operate when the furnace bonnet, limit control has rendered the stoker inoperative. The last arrangement allows the blower to circulate cold air, taken from the heated rooms, about the overheated furnace surface, thus driving the heat in the bonnet down to a normal furnace temperature.

More specifically the embodiment of my invention consists of an instrument panel 5 (Fig. 1) having mounted thereon a fire pilot control 6, an electromagnetic switch 7, an overload control 8 and a formica contact panel 9. The instrument panel may be enclosed in a suitable box 10 (Fig. 5) and placed on a warm air furnace 11. Electricity is introduced to the circuits through plug 10 by the power lines 110 and 120 which terminate at the contacts 11 and 12 positioned on the contact panel 9. Electromagnetic switch coils are connected to the feed contacts 11 and 12 by lead lines 13 and 14 respectively. A thermostat 15, positioned in a heated room, controls the action of the electromagnetic switch by being connected in its circuit by means of extension wires 18 and 19 which join wires 20 and 21 respectively by contacts 16 and 17 positioned on the contact panel. When the thermostat is closed, it completes the circuit in the electromagnet coils, thus charging the core to draw the hingedly mounted arm 22 downwardly. This action of the arm also carries the U-shaped circuit breaker 220 downwardly to close the circuit contact points 23 and 24 thereby supplying current from the contact 12 to the stoker motor 26, by completing the circuit 10, 110, 12, 252, 23, 220, 24, 251, 250 and 26. The return lead 27 of the stoker motor is connected to the contact 270, a wire 280 also engaging the contact being led to one side of the limit control 28 located above the bonnet in the furnace. Wire 29 runs from the limit control to the overload 8, a wire 30 being connected to the other side of the overload 35 and the contact 11 to complete the stoker circuit.

The fire pilot control 6 comprises a synchronous motor 31 connected on one side to the feed lines by the electric circuit 310, 57, 58, 11, and 40 110 and upon its other side by the circuit 320, 14, 12 and 120. The motor is positioned on a plate 32 (Fig. 2) whilst an intermediate plate 33, fastened to the instrument panel 5 is held in spaced relation to the plate 32 by spacer rods 34. Reduction gearing, indicated generally as 35, have their bearings in the intermediate plate and the plate 32. The gearing is driven by a motor gear 36 and rotates the shaft 37 which has a shoulder portion 38 provided to engage a cam 39 fastened to it by a set screw 40. The motor preferably rotates the cam in a clockwise direction, at the speed of one revolution per hour.

An indicator plate 41, fastened to the motor by bolt 42, is held in spaced relationship to panel 55 5 by a rod 43. A mercury tube switch 44, held by a clamp 45 is pivoted on a rod 46. One end of a bell crank lever 47 fastened to the clamp is adapted to engage the periphery of the cam 39. A weight 48 (Fig. 3) positioned on the free 60 end of the lever is provided to allow the lever to continually engage the periphery of the cam.

The periphery of the cam is made on an increasing radius and at the point of greatest radius has an offset portion 49. It is evident that the cam controls the inclination of the mercury tube and since the periphery of the cam is generally of small radius the tube will be held in the inclined position indicated in Fig. 1. In this position the pair of switch contacts 50 which operate the blower will be closed. One of these contact points is connected to the contact 250 of the supply line 25 by wire 51. The other contact point is wired to contact 52 by line 53 and 70 then led by wire 54 to the blower 55. A re-

turn wire 56 runs to the contact 57 which is connected to the feed contact 11 by wire 58.

When the cam has rotated so that the end of the bell crank lever engages a portion of the periphery of greatest radius, the mercury tube 5 will be inclined so that the pair of switch contacts 59 at the other end of the tube, will be closed, thus opening the blower contacts 50. Switch contacts 59 close the stoker motor circuit by allowing electricity from feed contact 12 10 to be led by wire 14, then to wire 60 and the contact 59 and thence by lead 61 to the motor circuit lead 25, through the stoker motor 26, the limit control 28, the overload 8 and back by wire 30 to the feed contact 11. 15

It is desirable to provide a means of regulating the length of time of stoker actuation by the fire pilot control. This is accomplished by providing an adjustable plate 62 to which the mercury tube pivot rod 46 is positioned. The adjustable plate is movably held by screw 63 to the indicator plate 41. A curved slot 64 in the plate 41, allows the rod 46 to move with the adjustable plate to regulate the relative position of the mercury tube switch to the cam 39. A set 25 screw 65 riding in a curved slot 66 holds the adjustable plate in any desired position indicated by the calibrations 660 on the indicator plate 41. By this means the effective length of cam periphery necessary for tilting the mercury 30 tube switch to the position for closing the stoker contacts, may be varied as shown by the words "Short" and "Long" on each side of the calibrations 66.

Operation: For purposes of clearness I now refer to the simplified wiring diagram of the device as disclosed in Fig. 6 in which the reference numbers employed in the foregoing specification have been used as far as practicable. Under normal cold weather conditions the thermostat 15 will demand heat when the room falls below a predetermined temperature. The thermostat will therefore operate to close the circuit in the coils of the electromagnetic switch 7 which are energized from the electric plug 10 by circuits 13, 110, 14, 120 thereby allowing the circuit contacts 23 and 24 to be closed to complete the electric circuit 10, 110, 251, 23, 24 and 25 to the stoker motor 26. Current then flows to the contact 250 where it continues to the stoker motor 26. The return wire 27 connects the stoker motor to the limit control 28 and the circuit is completed by line 28 to the overload 8 and line 30 to the feed line 25. Normally the mercury tube switch 44 is inclined so as to close the blower switch 55 contacts 50 and therefore a wire 51 led from the stoker motor supply line 25 will carry current to the contacts 50 which is returned by wire 53 to the blower 55. A return wire 56 is connected to the other side of the blower 55 which communicates with feed line 120. In this manner the stoker and the blower work in unison to supply heat to the rooms when the demand is made upon them by the thermostat. 55

The fire pilot control 6 operates independently 65 of the stoker motor and blower circuits. This is accomplished by periodically tilting the mercury tube switch 44 to a position which will close the stoker switch contacts 50 and open the blower switch contacts 59. A circuit will then be set up 70 from feed line 110 and wire 60 and the switch contacts 59. A return wire 61 leads to the stoker motor supply line 25 and thence to the stoker 26. The current is completed by line 27, limit control 28, wire 29, overload control 8 and wire 75

38 to the feed line 120. A current will not be sent to the blower because the blower contacts 50 are necessarily opened when stoker contacts 58 are closed. The blower being inactive, the heat 5 of the stoker activity will to some extent, remain about the furnace bonnet and warm air chamber.

My device also acts to prevent excessive heat from remaining about the furnace bonnet and warm air chamber. Under conditions that require 10 the thermostat to demand heat in such quantities as to make the limit control break the stoker motor circuit, the blower will continue to operate to carry off the excessive heat in the bonnet thus driving the temperature down to a normal one. This is accomplished by making the electric circuit 10, 110, 251, 23, 24, 25, 51, 50, 53, 55, 58 and 120. Because the limit control 8 is opened the stoker motor circuit 25, 26, 27, 28, 29, 30, 120 will remain inoperative.

20 I prefer to employ a warm air furnace 71 as set forth in Fig. 5 in conjunction with my mild weather control. The furnace casing 72 is substantially rectangular and consists of three separate compartments divided by insulating walls 25 73 and 74. The stoker unit is located in compartment 75 and comprises a hopper 76, a worm feed drive gearing 77, stoker blower 78 and the stoker motor 26. A hopper door 79 is located on the front casing of the furnace and communicates with the hopper by a suitable closed passageway. The central compartment 80 has a boiler plate furnace 81 located centrally thereof. A radiator 82 having a flue pipe connection 83 and a clean out door 84 is located behind the furnace. The limit control 28 is positioned on a suitable support 85 above the bonnet 86 of the furnace. The third compartment 87 contains a conventional air circulating blower 55 capable of drawing air from its two axial sides and forcing 30 it into the central compartment 80. One side of the blower communicates by an air conduit 88, located at the rear of and beneath the radiator, with the compartment 75. Cold air from the heated rooms is thereby drawn through the 35 pipe 89 and passes through the interchangeable air filters 90 into the conduit 88 and thence to the blower to be forced from the latter through an opening 91 into the compartment 80. Cold air is also drawn through pipe 92 and filters 93 into the other side of the blower and thence forced 40 into compartment 80. The circulating air is warmed by passing around the radiator and the boiler plate furnace and returns to the heated rooms by pipes 94. In this manner, it will be 45 understood, the cold air from the room is conditioned for its return to the rooms. My controls are suitably mounted in a conventional metal box 70 positioned on the front casing of the furnace and accessible by a door opening outwardly from the front casing. With reference to Fig. 1 the insulated wire 95, comprising the wires 18 and 19, leads from an opening in back of the control box 70 to the thermostat 19 located in the heated room. The insulated wire 96 consists of wires 54 and 56 and connects the blower 55 with the control box. The limit control 28 is connected with box 70 by the insulated double wire lead 97 whilst the insulated wire 98 carrying wires 25 and 27 connects the box with the stoker motor.

50 It is to be understood that my mild weather control can be employed satisfactorily in connection with an electrically operated means for actuating the heat circulating means, as for example, where a circulating pump is used to

stimulate the circulation of hot water. If the controls were used in this connection, the blower leads 54 and 56 would be wired to the actuating means of the circulating pump. Also my controls may be employed where an electrically operated means is used for actuating the feed supply means such as an oil burning furnace having a circulating blower. In this case the leads 25 and 27 would be wired to the means for actuating the oil feeding means.

5 What is claimed is:

1. In a circulating warm air furnace-stoker control, the combination of a stoker motor, a circuit for the motor, a thermostat adapted to open and close the circuit, an electric blower, 15 a circuit for the blower connected in parallel with the motor circuit and opened and closed by the thermostat, switch contacts in the motor circuit and in parallel with the thermostat, a time controlled mechanism adapted to open and 20 close the switch contacts in the motor circuit at regular intervals of time, and switch contacts connected in series in the blower circuit adapted to close the blower circuit when the motor circuit switch contacts are open and to open the 25 blower circuit when the motor circuit switch contacts are closed.

2. In a circulating warm air furnace-stoker control, the combination of a stoker motor, a circuit for the motor, a thermostat adapted to 30 open and close the circuit, an electric blower, a circuit for the blower connected in parallel in the motor circuit and opened and closed by the thermostat, a mercury tube, a pivotal mounting for said tube, switch contacts for the motor 35 circuit located in one end of the mercury tube and in parallel with the thermostat, a time controlled mechanism adapted to tilt the mercury tube to open and close the switch contacts in the motor circuit at regular intervals of time, and switch 40 contacts for the electric blower circuit located in the other end of the mercury tube and adapted to close the blower circuit when the motor circuit switch contacts are open and to open the 45 blower circuit when the motor circuit switch contacts are closed.

3. In a circulating warm air furnace-stoker control, the combination of a stoker motor, a circuit for the motor, a thermostat adapted to open and close the circuit, an electric blower, 50 a circuit for the blower connected in parallel with the motor circuit and opened or closed by the thermostat, a fire pilot control comprising a cam, a synchronous motor adapted to revolve the cam, a pivoted mercury tube, a bell crank 55 lever fastened to the mercury tube and adapted to engage the cam, the lever cooperating with the cam to regulate the inclination of the mercury tube, switch contacts for the motor circuit located in one end of the mercury tube and connected in parallel with the thermostat, said contacts adapted to be opened and closed at regular intervals of time by the fire pilot control, and switch contacts connected in series in the blower circuit, located in the other end of 60 the mercury tube switch and adapted to close the blower circuit when the motor circuit switch contacts are open and to open the blower circuit when the motor circuit switch contacts are closed.

4. In a circulating warm air furnace-stoker control, the combination of a stoker motor, a circuit for the motor, a limit control in series in the motor circuit, a thermostat adapted to open and close the circuit, an electric blower, a circuit 75

for the blower connected in parallel to the motor circuit and opened and closed by the thermostat, a mercury tube, switch contacts for the motor circuit located in one end of the mercury tube and in parallel with the thermostat, a time controlled mechanism adapted to tilt the mercury tube to open and close the switch contacts in the motor circuit at regular intervals of time, and switch contacts for the electric blower circuit located in the other end of the mercury tube and adapted to close the blower circuit when the motor circuit switch contacts are open and to open the blower circuit when the motor circuit switch contacts are closed, the blower circuit thereby being rendered operative when the limit control has opened the stoker motor circuit provided the mercury tube switch contacts in the blower circuit are closed.

5. In a furnace of the class described, the combination of an electrically operated fuel feeding means, a circuit for the electrically operated fuel feeding means, a thermostat adapted to open and close said circuit, an electrically operated heat circulating means, a circuit for the electrically operated heat circulating means connected in parallel with the circuit of the electrically operated fuel feeding means and opened and closed by the thermostat, switch contacts in the circuit for the electrically operated fuel feeding means and wired in parallel with the thermostat, a time controlled mechanism adapted to open and close the switch contacts in the electrically operated fuel feeding means at regular intervals of time, switch contacts connected in series with the electrically operated

heat circulating means and adapted to close the circuit for the electrically operated heat circulating means when the switch contacts for the electrically operated fuel feeding means are open and to open the switch contacts for the electrically operated heat circulating means when the switch contacts for the electrically operated fuel feeding means are closed.

6. In a furnace of the class described, the combination of an electrically operated fuel feeding means, a circuit for the electrically operated fuel means, a limit control interposed in the circuit for the electrically operated fuel feeding means, a thermostat adapted to open and close said circuit, an electrically operated heat circulating means, a circuit for the electrically operated heat circulating means connected in parallel with the circuit of the electrically operated fuel feeding means and opened and closed by the thermostat, switch contacts in the circuit for the electrically operated heat circulating means and wired in parallel with the thermostat, a time controlled mechanism adapted to open and close the switch contacts in the electrically operated fuel feeding means at regular intervals of time, switch contacts connected in series with the electrically operated heat circulating means and adapted to close the circuit for the electrically operated heat circulating means when the switch contacts for the electrically operated fuel feeding means are open and to open the switch contacts for the electrically operated heat circulating means when the switch contacts for the electrically operated fuel feeding means are closed.

ARTHUR V. SAMPSEL. 35
